UNITED STATES PATENT OFFICE.

WILLIAM A. PRINGLE, OF NIAGARA FALLS, NEW YORK, ASSIGNOR, BY MESNE ASSIGNMENTS, TO AMERICAN SALES BOOK COMPANY, LIMITED, A CORPORATION OF ONTARIO, CANADA.

PRINTING APPARATUS.

1,105,042.

Specification of Letters Patent.

Patented July 28, 1914.

Original application filed December 5, 1906, Serial No. 346,392. Divided and this application filed June 27, 1910. Serial No. 568,998.

To all whom it may concern:

Be it known that I, WILLIAM A. PRINGLE, a citizen of the United States, residing at Niagara Falls, in the county of Niagara and State of New York, have invented certain new and useful Improvements in Printing Apparatus, of which the following is a full, clear, and exact description, such as will enable others skilled in the art to which it applies to make and use the same.

This invention relates to printing mechanism for preparing the web for the manufacture of sales books and the like.

One of the objects of the invention is to provide simple and efficient means for perforating webs.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

Referring now to the drawings, wherein is illustrated one of various possible embodiments of my invention, Figure 1 is a transverse sectional view taken through the delivery mechanism of a printing press, showing the said attachment applied thereto. Fig. 2 is a view in side elevation of the said attachment. Fig. 3 is a view in side elevation of the male perforating cylinder. Fig. 4 is a similar view of the female perforating cylinder. Fig. 5 is a vertical sectional view taken through the perforating cylinders showing the position of the parts when inoperative relation. Fig. 6 is a similar view showing the position of the parts when in operative relation. Fig. 7 is a view in perspective of the perforating device. Fig. 8 is a similar view of the member which coacts with the perforating device.

Similar reference characters refer to similar parts throughout the several views of the drawings.

Referring now to the drawings, 1 indicates the side walls of a portion of a printing press, which serve as supports for the several cylinders employed for feeding and printing upon traveling webs. The mechanism constituting the printing press is not shown herein as the same constitutes no es-

sential part of my invention. For the purposes of describing this invention, it will be understood, however, that feed rolls, which are indicated generally at 2, are adapted to deliver from the printing mechanism a plurality of webs A and B, which have been acted upon thereby, said webs traveling side by side, but in different horizontal planes, between said rolls. This independent attachment or said device, which is denoted generally by 8, as shown in the drawings, is attached to the side of the printing press, as by means of clamp bolts 9, and the relation of this device to the press is clearly shown in Fig. 1 of the drawings. The frame of the said device is comprised of a pair of parallelly disposed walls 9' and 10 which form journal supports for the several rolls and cylinders employed therein to effect the different operations upon the web C. This web, which is fed from a suitable source of supply, not herein shown, is first received between a pair of drawing rolls 11 and 12, roll 11 being spring-pressed toward roll 12 by means of a retractile spring 13 and is capable of being swung therefrom, to allow the web to be inserted, by means of a handle 14. Web C then passes over roll 12 and between it and a similar drawing roll 15 and is received between a printing couple constituted by a plate cylinder 16 and an impression cylinder 17, which effects printing of any desired inscription upon the traveling web. The web is then carried along impression cylinder 17 to be engaged by the numbering devices carried upon a cylinder 18 which coacts therewith, the construction of which is particularly described and claimed in my co-pending application Serial Number 346,392 filed December 5, 1906 of which this application is a division. This application subsequently resulted in Patent 974,428, issued November 1, 1910.

The web after being acted upon by the numbering mechanism is perforated by means of mechanism carried by the pair of mating cylinders 19 and 20 between which the web next passes. The perforating mechanism, as shown in Figs. 3 to 8, inclusive, comprises a female cylinder 19 and a male cylinder 20 which mutually co-act with each other. Female cylinder 19 is provided with a longitudinally extending recess within

which is set a strip 21 provided at its outer lateral edge with a plurality of spaced members or posts 22. Male cylinder 20 is also provided with a longitudinally extending recess to receive a strip 23 which carries a blade 24, the outer lateral side of which is provided with a plurality of spaced members 25, the end of each of which is bifurcated and formed into a pair of short perforating points 26. These points, when the cylinders are rotated, enter between the posts of strip 21. Strip 23 which carries the perforating blade is capable of adjustment to carry blade 24 in an outward direction by means of adjusting screws 27 extending transversely through the cylinder, said strip being held in adjusted position by means of set screws 28. Mounted in recess 29 of cylinder 20 is a strip 30 which constitutes a clearing bar for the perforating points, said strip lying in engagement with blade 24. This strip is held in recess 29 by means of screws 31, which also extend transversely through the cylinder, and is urged in an outward direction by means of retractile springs 32, which engage at their outer ends with the strip and at their inner ends with shoulders provided in the recess through which the screws extend. This clearing blade operates to force the web from the perforating points when the same are extending therethrough and prevents the web from being torn by said points when it is drawn from between the perforating cylinders by the drawing rolls.

It will accordingly be seen that I have provided mechanism whereby the capacity of a printing press of the above type may be increased in an extremely simple and efficient manner. The attachment, while always in position to be utilized, may be thrown out at will without affecting any of the other operations of the press. The numbering of the web is effected in an accurate and positive manner and the construction of the perforating mechanism insures that the web will not be torn or otherwise mutilated during the perforating operation.

As many changes could be made in the above construction and many apparently widely different embodiments of this invention could be made without departing

from the scope thereof, it is intended that all matter contained in the above description or shown in the accompanying drawings shall be interpreted as illustrative and not in a limiting sense.

Having described my invention, what I claim as new and desire to secure by Letters Patent is:

1. In perforating mechanism for traveling webs, in combination, a plurality of mating cylinders, one of said cylinders being provided with a device having a plurality of spaced members, the other of said cylinders having affixed thereto a plurality of spaced members each of which carries a plurality of perforating points, means for adjusting one of the sets of spaced members toward and from the other, said perforating points being adapted to take between the spaced members upon the other of the cylinders when said cylinders are mutually rotated whereby the web passing therebetween is perforated, and a yielding member mounted adjacent and extending parallel with said perforating points adapted to free the said points from the web when said web has been perforated thereby.

2. In perforating mechanism for printing presses, in combination, a male cylinder provided with a recess in which is set a blade having a plurality of spaced members, each of which is provided with a pair of perforating points, a female cylinder having a recess within which is set a comb device composed of square teeth between each of the teeth of which one of said pairs of perforating points is adapted to be received, a clearing bar mounted in the recess of said male cylinder adjacent the perforating points of said blade adapted to be retracted when said perforating means is co-acting to perforate a web, and spring means for forcing said clearing bar in an outward direction whereby said perforating points will be cleared of said web after each perforating operation.

In testimony whereof I affix my signature, in the presence of two witnesses.

WILLIAM A. PRINGLE.
